ACTION TOY

Maurice Greenman, Buffalo, N. Y.

Application May 13, 1940, Serial No. 334,767

7-Claims. (Cl. 46—99)

This invention relates to action toys of the type adapted to move along a surface on wheels or the like.

The present invention has as one of its objects the provision of a toy wherein an animal simulating portion is provided with articulated legs for imparting to the animal figure the appearance of natural motion and animation when the toy is moving along a surface.

A further object of the invention resides in the association of a rider figure with an animal figure in such manner that rocking movements of the animal figure and the rider figure cooperate to produce an effect of even greater animation.

In a preferred form of the invention I provide means for periodically producing sounds simulating the report of a pistol or other firearm and for cooperation with such means the rider figure is provided with a portion simulating a firearm in position for use. In the form in which my invention is shown in the drawing and described in the ensuing specification, the conjoint movements of the animal and rider figures are synchronized with the sounding means in such a way that the relationship between the pistol report and the body movement of the rider figure is emphasized by the synchronization.

Further objects and advantages of the action toy of my invention will appear from a perusal of the ensuing specification, in connection with the drawing, and a study of the appended claims. It will be apparent to those skilled in the art that many modifications and alterations may be made in the specific form illustrated and described herein without departing from the spirit or scope of my invention.

In the drawing:

Fig. 1 is an elevational view of the action toy of my invention in a preferred form;

Fig. 2 is a top plan view thereof; and

Fig. 3 is a fragmentary perspective view of the rear part of the base portion of the toy of Figs. 1 and 2.

In the drawing like characters of reference denote like parts, and the numeral 10 designates generally a supporting base which may conveniently comprise a relatively flat top portion 11 and a pair of parallel depending side flanges 12 and 13. In the drawing the base 10 is shown as having a tapering forwardly projecting portion 14 provided with an opening 15 for receiving a cord or the like for drawing the toy along a surface.

The base 10 has associated therewith a pair of front wheels 16 which are secured to opposite

ends of an axle 17 which is journaled in the opposite side flanges 12 and 13 of the base 10. There is further provided a pair of rear wheels 18 which are secured to opposite ends of an axle 19 which is likewise journaled in the opposite side flanges 12 and 13 of the base 10.

One of the pairs of wheels is intended to perform a further driving function and while either pair of wheels may serve in this capacity, in the 10 illustrated form the rear wheels 18 with their associated axle 19 serve to activate other elements of the toy. To this end, the ends of the axle 19 are preferably non-circular for assembly in driving engagement with the wheels 18. As 15 shown in Fig. 3, the ends of the axle 19 are provided with longitudinal serrations, but any convenient mode of fixing the pair of wheels 18 with respect to the axle 19 will serve the purpose. In the specific form illustrated the front axle 17 20 need not have driving engagement with its associated wheels 16 and may, therefore, comprise a rod riveted over at its opposite ends.

Referring to Fig. 1, the body of the animal including the head is designated by the numeral 23 and such body is arranged to be pivotally disposed upon the base 10 as by means of a U-shaped support 24 whose base may be spot welded or otherwise secured to the upper flat portion 11 of the base 10 at its underside with the upstanding arms of the support extending through suitable openings in the portion 11 of the base 10. The upper terminal portions of the support 24 are perforated to receive a pivot pin 25 which also passes through an opening provided in the body 23 of the animal figure.

Control of the pivotal movements of the body 23 of the animal about the pivot pin 25 is preferably effected by means of a pair of elements 27 which form the legs of the animal at one end thereof, in the present embodiment the rear, and which serve as pitmans.

Each of the rear legs 27 is pivoted at its upper end to a pin 28 which passes through the body 23 of the animal figure and each of the legs 27 is pivoted at its lower end to an eccentric point on one of the rear wheels 18 by means of a pivot pin 29 which may be a nail or other suitable pivot device.

The pair of front legs of the animal are in the 50 present example each formed by a pair of links 30 and 31. The upper link 30 has its upper end pivotally attached to the body of the animal by a pivot pin 32 and the lower link 31 has its lower end pivotally attached to an eccentric point on 55 one of the front wheels 16 as at 33. The other

ends of each of the links 31 are pivotally connected to each other intermediate the body of the animal and the base of the toy as at 34.

Various species of animals may be simulated in pursuing the principles of my invention and for this reason various modifications in the specific arrangement of the legs and pitmans which comprise the legs of the animal may be resorted to. The essential thing is that either the front or the rear legs of the animal be rigid to serve as a driving crank. The provision of one rigid leg, either front or rear, for the driving elements, in combination with an articulated leg of the kind shown at 30, 31 in Fig. 1, permits of free rocking movement of the body of the animal 23 on the pivot pin 25, regardless of the relative angular positions of the front and rear wheels and with no necessity for synchronization thereof. This arrangement eliminates any possibility of binding or locking of the linkages besides adding materially to the impression of natural animation which is produced when the toy is in motion.

To give stability to the device, it is preferable that the tread of the wheels be of substantially greater width than the body 23 of the animal, and in the illustrated form this difference in width is compensated for by disposing spacing collars 38 between the rear legs 27 and the body 23 of the animal at opposite sides of the latter, the pivot pin 28 passing through both spacing collars 38 as well as through the pair of legs 27 and the body 23 of the animal. Similar spacing collars, designated 39, may be provided in conjunction with the pivotal connection of the upper ends of the pair of upper links 30 which form a part of the front leg construction of the device.

The rider figure, designated generally 40 in Fig. 1, may, if desired, be rigidly associated with the animal body 23. In a preferred form, however, I provide a body member 41 which has secured to the lower portion thereof a pair of leg elements 42 which straddle the body 23 of the animal figure and are pivotally disposed upon the pivot pin 25 previously described. To provide ample clearance between the legs 42 and the body member 23 for reception of the upper ends of the U-shaped support 24, spacing shims may be disposed between the leg members 42 and the body member 41 of the rider at opposite sides of the latter, and such shims are shown at 54 in Fig. 2. Instead of using the shims 54 the lower ends of the legs 42 or the lower medial portion of the body 23 of the animal may be suitably notched to accommodate the upper ends of the support 24.

The body 23 of the animal figure is provided at its upper side with a saddle simulating portion 43 and the lower portion of the body member 41 of the rider figure is formed approximately as shown at 44 in Fig. 1, whereby the body of the rider may have limited longitudinal rocking movement in the saddle simulating portion 43. The rider is shown in Fig. 1 at the rear limit of his rocking movement in the saddle, forward movement being limited by engagement of the lower part 44 of the body portion 41 with the back of the saddle horn 45. Rocking movements of the rider figure in the saddle 43 are engendered by passage of the center of gravity of the rider figure back and forth across a vertical line through the pivot pin 25 by reason of the primary rocking movement of the animal figure caused by the crank and pitman action of the rear legs 27.

In the illustrated embodiment the rider is

shown as bearing an extended weapon in the form of a pistol 47. A unique part of the action of the present toy is brought about by producing a sound simulating a pistol report each time the rider lurches forward in the saddle 43 by reason of a forward rocking movement of the animal figure which causes the center of gravity of the rider figure to pass over top dead center and fall to the forward part of the saddle 43.

The sounding means may comprise a leaf spring 48 having an end secured to the top portion 11 of the base member 12, and as shown in Fig. 3, such end may be disposed between the under side of the portion 11 and the base of the supporting member 24 and spot welded into an integral assembly therewith. The outer free end of the leaf spring 48, the rear end in the form illustrated, is bent downwardly and outwardly to provide a portion 50 which is engageable by a crank 51 which may be conveniently formed by offsetting an intermediate portion of the rear axle 19 as shown in Figs. 2 and 3. The leaf spring need not, of course, be secured with the support 24 and if a longer spring appears desirable the spring may be attached forwardly of the support 24.

As the device moves forwardly on its wheels 16 and 18, the crank portion 51 engages the portion 50 of the leaf spring 48 and flexes the leaf spring downwardly about its connection to the portion 11 of the base 10 until the crank portion 51 rides rearwardly off the portion 50. The leaf spring is then abruptly released and strikes sharply against the underside of the portion 11 of the base 10. This striking produces a sound which simulates a pistol report, and the elements are preferably so proportioned that the sound is timed to occur as the rider reaches his forward limit of movement in the saddle, thereby simulating the natural forward movement of the user of a pistol in discharging the same.

It is obvious that while an animal resembling a horse has been illustrated in the drawing, other species of animal may be embodied in the construction, and that the rider may be costumed in any manner, preferably in accord with the kind of animal which is simulated.

What is claimed is:

1. In an action toy, a base and wheels associated therewith to facilitate movement of said toy along a surface, a figure representing the body of an animal supported upon said base for pivotal movement about an intermediate point, said figure having a fore leg and a rear leg, one of said legs being pivotally connected at its upper end to the body of said figure and pivotally connected at its lower end to an eccentric point on a wheel of said toy, whereby movement of said toy on its wheels imparts a rocking movement to said animal figure, the other of said legs comprising a pair of links pivotally connected to each other at one end of each, the other end of one link being pivotally connected to the body of said figure and the other end of the other link being pivotally connected to a wheel at an eccentric point thereon.

2. In an action toy, a base and wheels associated therewith to facilitate movement of said toy along a surface, a figure representing the body of an animal supported upon said base for pivotal movement about an intermediate point, said figure having a fore leg and a rear leg, one of said legs being pivotally connected at its upper end to the body of said figure and pivotally connected at its lower end to an eccentric point on a

wheel of said toy, whereby movement of said toy on its wheels imparts a rocking movement to said animal figure, a rider figure disposed upon said animal figure and represented as carrying a firearm in position for use, said rider figure being pivotally secured to said animal figure adjacent the lower portion of the former for rocking movement limited in each direction by engagement of said rider figure with portions of the animal figure with the center of gravity of the rider figure above its pivotal connection and so arranged that the rider lurches to its forward limit of rocking movement on said animal figure toward the conclusion of a forward rocking movement of the animal figure and moves to its rearward limit of rocking movement on said animal figure during rearward rocking movements of the animal figure, and means operated from said wheel for producing a report during each rotation of said wheel, such means being timed to produce said sound as the rider and animal figures reach their extremes of forward rocking movement.

3. In an action toy, a base and wheels associated therewith to facilitate movement of said toy along a surface, a figure representing the body of an animal supported upon said base for pivotal movement about an intermediate point, said figure having a fore leg and a rear leg, one of said legs being pivotally connected at its upper end to said figure body and pivotally connected at its lower end to an eccentric point on a wheel of said toy, whereby movement of said toy on its wheels imparts a rocking movement to said animal figure, the other leg comprising a pair of links pivotally connected to each other at one end of each, the other end of one link being pivotally connected to said figure body and the other end of the other link being pivotally connected to the lower portion of said toy.

4. In an action toy, a base and wheels associated therewith to facilitate movement of said toy along a surface, a figure representing the body of an animal supported upon said base for pivotal movement about an intermediate point, said figure having a fore leg and a rear leg, one of said legs being pivotally connected at its upper end to the body of said figure and pivotally connected at its lower end to an eccentric point on a wheel of said toy, whereby movement of said toy on its wheels imparts a rocking movement to said animal figure, the other of said legs comprising a pair of links pivotally connected to each other at one end of each, the other end of one link being pivotally connected to the body of said figure and the other end of the other link being pivotally connected to the lower portion of said toy, the links of said other leg being so proportioned with respect to the remaining structure that the pivot connecting the two links is normally disposed substantially spaced from a line connecting the other two pivotal connections of the links whereby the links are normally obliquely disposed.

5. In an action toy, a base and wheels asso-

ciated therewith to facilitate movement of said toy along a surface, a figure representing the body of an animal supported by said base for pivotal movement about an intermediate point, 5 said figure having a fore leg and a rear leg, one of said legs being pivotally connected at its upper end to said figure body and at its lower end to an eccentric point on a wheel at one end of said toy to serve as a pitman and impart rocking movement to said animal figure, the other of said legs comprising a pair of links pivoted to each other at one end of each, the other end of one link being pivotally connected to said figure body and the other end of the other link being pivotally connected to an eccentric point on a wheel at the other end of said toy, said pivoted links being disposed at an oblique angle and forming an articulated leg adapted for animated movement without interference with said other leg in the production of rocking movement of the animal body by the latter.

6. In an action toy, a base and wheels associated therewith to facilitate movement of said toy along a surface, a figure representing the body of an animal supported upon said base for pivotal movement about an intermediate point, said figure having a fore leg and a rear leg, one of said legs being pivotally connected at its upper end to the body of said figure and pivotally connected at its lower end to an eccentric point on a wheel of said toy, whereby movement of said toy on its wheels imparts a rocking movement to said animal figure, the other of said legs comprising a pair of links pivotally connected to each other at one end of each, the other end of one link being pivotally connected to the body of said figure and the other end of the other link being pivotally connected to the lower portion of said toy, a rider figure disposed upon said animal figure and represented as carrying a firearm in position for use, means operated from said wheel for producing a report during each rotation of said wheel, such means being timed to produce said sound as the rider and animal figures reach one of their extremes of rocking movement.

7. In an action toy, a base and wheels associated therewith to facilitate movement of said toy along a surface, a figure representing the body of an animal supported upon said base for pivotal movement about an intermediate point, said figure having a fore leg and a rear leg, one of said legs being pivotally connected at its upper end to said figure body and pivotally connected at its lower end to an eccentric point with respect to the axis of rotation of a wheel of said toy, whereby movement of said toy on its wheels imparts a rocking movement to said animal figure, the other leg comprising a pair of links pivotally connected to each other at one end of each, the other end of one link being pivotally connected to said figure body and the other end of the other link being pivotally connected to the lower portion of said toy.

MAURICE GREENMAN.
